UNITED STATES PATENT OFFICE.

RALPH H. UPSON, OF AKRON, OHIO, ASSIGNOR TO THE GOODYEAR TIRE & RUBBER COMPANY, OF AKRON, OHIO, A CORPORATION OF OHIO.

AIRSHIP AND THE LIKE.

Application filed December 5, 1919. Serial No. 342,735.

To all whom it may concern:

Be it known that I, RALPH H. UPSON, a citizen of the United States, and resident of Akron, Ohio, have invented new and useful Improvements in Airships and the like, of which the following is a specification.

My present invention relates to new and useful improvements in dirigible balloons, and has particular reference to the construction of balloonets and the air supplying apparatus employed in connection therewith.

In the accompanying drawing, wherein a practical embodiment of my present invention is illustrated:

15 Fig. 1 is a side elevation of the balloon with certain interior parts of the balloon indicated in dotted lines;

Fig. 2 is a vertical longitudinal sectional view; and

20 Fig. 3 is a cross section on the line 3—3 of Fig. 1.

In general, the balloon shown in the accompanying drawing comprises an envelope 10, a fuselage 11 wherein are mounted a 25 propelling engine 12, a blower 13, a water ballast tank 15 and a plurality of gasoline tanks 16.

The specific construction of the fuselage and the arrangement of the various apparatus contained therein form no part of my present invention, and the fuselage has been illustrated in connection with the invention only that a clear understanding of the improved construction and advantages thereof 35 may be clearly understood.

The necessary elevators and steering planes or rudders, together with the controllers therefor, and suspension ropes for the fuselage, have been illustrated for the 40 purposes of affording a clearer understanding of the present invention.

As is well known, it is customary to provide dirigible balloons of the blimp type, with balloonets into which air may be admitted at will for the purpose of equalizing the various gas pressures in the envelope, whereby the envelope may be kept taut and filled out to its proper conformation at all times.

50 In the accompanying drawings I have shown two balloonets 17 and 18, located respectively fore and aft of the envelope. These two balloonets are connected by a conduit through which the air is forced into

the balloonets from either the blower 13 or a 55 scoop 20, as will be later explained more in detail.

The conduit 19 is preferably in the form of a semi-circular tube and is located interiorly of the envelope in order that the air resistance of the balloon may be minimized. The scoop 20 is suspended from the envelope 10 and located immediately behind the propeller, (see Fig. 1), in order that the air current set up by the propeller will cause 60 the passage of a volume of air through the scoop 20 into the conduit. At the upper end of the scoop 20 is located a pair of flap valves 21 which open inwardly and permit the air to pass from the scoop tube into the 65 conduit for subsequent passage into the balloonets. These flap valves 21 are manually controlled from the pilot's car, at will. A partition 22, located across the manifold 19 between the two valves 21, divides the manifold into two sections, for a purpose later 70 to be described.

As thus far described, a current of air passes from the propeller into the scoop 20, through the scoop to the valves 21. Here 75 the air is stopped, unless the pilot desires to inflate either or both balloonets, whereupon he will open, say, the valve to the front balloonet, which permits the air to enter the forward section of the manifold 19 and thence into the balloonet. When the desired pressure is obtained, the valve 21 is again closed. The above description also applies to the rear balloonet, or both, as the case 80 may be.

The foregoing description describes a practical means for inflating the balloonets, provided, of course, the engine is operating. Should the engine fail, however, other means are necessitated if a prolonged flight is desired. To this end I employ the use of the 85 following:

An auxiliary manifold or conduit 24 is, in this instance, secured to the envelope 10 directly beneath the inner manifold 19, but 90 on the outside of the bag and communicates with the scoop 20 at its forward end, being closed at its opposite end. It is to be understood, however, that both conduits may be placed either inside of the bag, or on the 95 outside, as may be desired. A cylindrical housing 25 is secured within an opening 26 provided in the lower surface of the mani-

fold 24 near its rear end, and forms a means of attachment and closure for a collapsible tube 27. The tube 27 is designed to be folded or coiled up within the housing 25 when not in use and is held in such manner by a hinged cap 28 which is adapted to be swung out of place by means of a hand cord 29 secured to the cap. The free end of the collapsible tube 27 is designed to be fitted 10 over the open end of the blower 13, when released and dropped from the housing 25.

The blower forces air into the collapsible tube 27 and through the auxiliary manifold 24 to the valves 21, whereupon it is transferred to the balloonets at will by proper manipulation of the valves. To prevent the passage of air out through the scoop 20, a manually operated valve 30 is located within the scoop, adjacent the junction of the scoop 20 with the auxiliary duct 24.

The balloonets 17 and 18 are arranged, as will be noted, in such a manner that when the air pressure in the balloonets falls to a low point, the fabric forming the balloonets 25 will not fall to a position which would cause the air inlet ends of the main air conduit to be closed or clogged. In this connection it is to be noted that this is a feature of particular importance, since the principal 30 objection to the floating type of balloonet heretofore employed in "blimp" construction has been that when the pressure in the balloonets falls to a low point the fabric of the balloonets frequently closes over the inlet 35 opening for the air. By the present construction of the balloonet 17, the greatest cross sectional area of the balloonet is arranged distant from the end portions of the horizontal conduit 19, therefore, the mouth 40 of this balloonet will be open and free for the passage of air under all conditions, as will be apparent. The construction of the balloonet 18 is such that it bulges forwardly and outwardly over the rear end of the conduit 45 19, as shown at 31. By virtue of this construction when the balloonet 18 collapses the forward end thereof folds over and around the rear end of the conduit 19, and leaves the inlet opening thereto unobstructed.

It will be understood, of course, that my present invention is concerned principally with the arrangement of the balloonets 17 and 18, the manner in which the air is fed thereto, and the means by which this feeding of the air is accomplished, and does not concern at all the specific construction of the envelope or the elevators therefor, nor the rigging by which the fuselage is suspended 55 from the envelope, nor the construction nor design of the fuselage, nor of any of the contained parts thereof.

Although I have shown and specifically described but a single application of my invention, it is obvious that other applications

may be found therefor and minor changes made in the construction thereof without departing from the spirit or scope of the invention and I desire, therefore, that no limitations shall be imposed except such as indicated in the appended claims.

What I claim is:

1. The combination with the gas bag of a balloon, of a main conduit arranged in the lower interior part of the gas bag, balloonets disposed in the gas bag and connected to the end portions of the said main conduit, an auxiliary conduit arranged on the exterior of the gas bag and connected with the main conduit, a blower, and a tube connectible to said blower and said auxiliary conduit. 75

2. The combination with the gas bag of a balloon, of a main conduit arranged in the lower part of the gas bag, balloonets disposed in the gas bag and connected to the end portions of the main conduit, an auxiliary conduit arranged on the exterior of the gas bag and connected with the main conduit, a blower, a tube connectible to said blower and said auxiliary conduit, and a scoop connected to said auxiliary conduit and having its mouth disposed adjacent to the propeller of the balloon. 85

3. The combination with the gas bag of a balloon, of a main conduit arranged in the lower part of the gas bag, balloonets disposed in the gas bag and connected to the end portions of the said main conduit, an auxiliary conduit arranged on the exterior of the gas bag and connected with said main conduit, a blower, a collapsible tube connectible to said blower and said auxiliary conduit, and a scoop connected to said auxiliary conduit and having its mouth disposed adjacent to the propeller of the balloon. 95

4. The combination with the gas bag of a balloon, of a main conduit arranged in the lower part of the gas bag, balloonets disposed in the gas bag and connected to the end portions of the said main conduit, an auxiliary conduit arranged on the exterior of the gas bag and connected with the said main conduit, said auxiliary conduit being provided with an opening, a blower, a housing mounted on the auxiliary conduit at said opening, and a collapsible tube arranged in said housing, said collapsible tube having one end thereof connected to the housing and having the other end thereof connectible to the outlet of said blower. 110

5. The combination with the gas bag of a balloon, of a main conduit arranged in the lower part of the gas bag, balloonets disposed in the gas bag and connected to the end portions of the said main conduit, an auxiliary conduit arranged on the exterior of the gas bag and connected with the said main conduit, said auxiliary conduit being provided with an opening, and a scoop con- 125

nected to said auxiliary conduit, said scoop having its mouth disposed adjacent to the propeller of the balloon.

6. The combination with the gas bag of a 5 balloon, of a main conduit arranged interiorly of the bag, balloonets connected to the end of the said main conduit, an auxiliary conduit also arranged interiorly of the bag and connected with said main conduit, a blower, 10 a collapsible tube connectible to said blower and said auxiliary conduit, and a scoop connected to said main conduit and said auxiliary conduit and having its mouth disposed adjacent to the propeller of the balloon.
- 15 7. The combination with the gas bag of a balloon, of a conduit arranged in the lower part of the gas bag, balloonets connected to the ends of the conduit and disposed respectively at the nose 20 and stern of the balloonet, and means exterior of the gas bag for passing air into said conduit, said balloonets being arranged with their greatest cross sectional area disposed distant from the connection to the 25 said conduit.

8. The combination with a balloon embodying a gas bag, a propeller, and a plurality of air balloonets for controlling the inflation pressure of the balloon, of an air 30 scoop communicating with said balloonets and adapted to receive air for inflating said balloonets from the air stream of the propeller, an auxiliary device communicating with said balloonets and adapted to supply 35 air thereto, and means common to said scoop and said auxiliary air supply for selectively controlling the supply of air to the respective balloonets.

9. The combination with a balloon em-

bodying a gas bag, a propeller, and an air 40 balloonet for controlling the inflation pressure of the balloon, of an air scoop communicating with said balloonet and adapted to receive air for inflating said balloonet from the air stream of the propeller, and an auxiliary air supply adapted to be connected 45 to said balloonet.

10. The combination with a balloon embodying a gas bag, a propeller and an air 50 balloonet for controlling the inflation pressure of the balloon, of an air scoop communicating with said balloonet and adapted to receive air for inflating said balloonet from the air stream of the propeller, a blower, 55 means for connecting the blower to the balloonet, and means for closing the communication with said air scoop during the supply of air to said balloonet from the blower.

11. The combination with a balloon embodying a gas bag, a propeller, and an air 60 balloonet for controlling the inflation pressure of the balloon, of an air scoop communicating with said balloonet and adapted to supply air thereto from the air stream of the propeller, the pressure of the air stream 65 of the propeller constituting the sole pressure means for forcing air through said scoop, an auxiliary blower, and means for temporarily connecting the blower to the balloonet, said blower being normally disconnected from said balloonet. 70

In witness whereof I have hereunto signed my name in the presence of two subscribing witnesses.

RALPH H. UPSON.
